(57) **CLAIM**

The ornamental design for an electric toothbrush assembly as shown and described.

DESCRIPTION

FIG. 1 is a front elevational view of an electric toothbrush assembly showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a top, front and right side perspective view thereof;

FIG. 8 is a bottom, rear and left side perspective view thereof;

FIG. 9 is a top, front and right side perspective view showing the electric toothbrush assembly in a disassembled state; and,

FIG. 10 is an enlarged view of portion 10 in FIG. 8.

The broken lines in the drawings illustrate portions of the electric toothbrush assembly which form no part of the claimed design.

The dot-dot-dashed lines illustrate the boundary of the enlarged view and form no part of the claimed design.
